THERMOSTAT

Edward Bletz, Lexington, Ohio, assignor to Westinghouse Electric & Manufacturing Company, East Pittsburgh, Pa., a corporation of Pennsylvania

Application April 29, 1939, Serial No. 270,813

7 Claims. (Cl. 200—138)

My invention relates to heat-responsive devices, and more particularly to bimetallic thermostats.

An object of my invention is to provide a thermostat having a bimetallic member, portions of which move, upon increasing temperatures, first toward cooperating contacts and then at selectively predetermined temperature values in an opposite direction away from the contacts for disengagement thereof.

A further object of my invention is to provide a thermostat having a bimetallic member which rotatively flexes for a predetermined distance and then bows in a reverse direction to actuate cooperating contacts.

Another object of my invention is to provide a thermostat having a bimetallic member adapted to carry a contact intermediate the ends thereof and to increase the contact pressure of cooperating contacts by flexing towards the contacts with an increase in temperature thereof.

Still another object of my invention is to provide a thermostat having a bimetallic member which upon an increase in temperature thereof rotatively flexes in a direction away from the high expansive side to a selective predetermined point, whereupon a portion of the bimetallic member will reverse its rotation and move or bow towards the high expansive side for effecting disengagement of the contacts.

Other objects of my invention will either be pointed out specifically in the course of the following description of a device embodying my invention, or will be apparent from such description.

In the accompanying drawing,

Figure 1 is a top plan view of a device embodying my invention;

Figs. 2, 3 and 4 are sectional views taken along the line II—II of Fig. 1, illustrating the device in various operating positions;

Fig. 5 is a top plan view of a modified form of the device shown in Fig. 1;

Figs. 6, 7 and 8 are sectional views taken along the line VI—VI of Fig. 5, illustrating the device in its various operating positions;

Fig. 9 is a top plan view of an additional modification of the device shown in Fig. 1; and

Figs. 10, 11 and 12 illustrate the device of Fig. 9 in its various operating positions.

Referring in particular to Figs. 1 to 4, inclusive, of the accompanying drawing, I show a thermostatic device 10, including a base or supporting structure 12, a bimetallic member 14, cooperating contacts 16 and an adjusting device 18 supported

by the structure 12 and operatively associated with the bimetallic member 14 for controlling the operation thereof.

The base 12 is formed, in this instance, of an elongated metallic strip into substantially an inverted U-shaped member having outwardly extending supporting flanges 20 and 22 adapted to rigidly attach the base or structure 12 to any desired device. It is to be understood that, while the base 12 is illustrated as being formed of a metallic composition, such base or supporting structure may be formed from any suitable phenolic resin or the like.

The bimetallic member 14 is, in this instance, an elongated strip-type thermostatic member with an aperture 24 located intermediate the ends thereof for a purpose hereinafter described. The bimetallic member 14 is rigidly attached to the base or supporting structure 12 by means of a suitable block or spacer 26 and a screw 28. This method of fastening the strip-type bimetallic member 14 to the supporting structure 12 permits such bimetallic member to flex about the spacer 26 of base 12 as a fulcrum.

The relatively high expansive material of the bimetallic member 14 is, in this instance, located on the lower side thereof. The application of heat thus causes the free end of the bimetallic member 14 to rotatively flex upwardly or away from the high expansive side in a well-known manner. However, when the movement of the free end is stopped and both ends of the bimetallic member 14 are restrained from upward movement, the central portion of the bimetallic member will reverse its travel and bow downwardly or toward the high expansive side, as hereinafter more fully set forth. This, in turn, actuates the cooperating contacts 16 in the manner as hereinafter described.

The cooperating contacts 16 include a stationary contact 30 and a movable contact 32 which are respectively associated with suitable terminals 34 and 36. The contact 30 is, in this instance, rigidly attached to the lower surface of the central portion of the base or supporting structure 12 by means of the terminal 34. The terminal 34 has a rivet portion 37 located on the lower portion thereof. This rivet portion 37 extends through the supporting structure 12 and contact 30 where it is spun or riveted over against the contact 30. Suitable insulating members 38 are positioned intermediate the terminal 34, contact 30 and the supporting structure 12 to suitably insulate the terminal 34 and contact 30 from the supporting structure 12.

The movable contact 32 is flexibly or loosely attached to the supporting structure 12 by means of the second terminal 36 and flexible mounting member 44. The terminal 36 has a downwardly extending rivet portion 40 functionally integral therewith. The rivet portion 40 is adapted to extend through the supporting structure 12, a suitable spacing member 42 and the flexible mounting member 44 to the supporting structure 12. Suitable insulating members 39 may likewise be positioned intermediate the terminal 36 and spacer member 42 to insulate such members from the supporting structure 12. The flexible mounting member 44 may be of any suitable resilient current carrying material, such as stainless steel. The resilient supporting member 44 extends substantially parallel to the bimetallic member 14 intermediate such member and the supporting structure 12, and has rigidly attached at the free end thereof the movable contact 32.

A suitable pin 46 is insulatedly attached to the flexible mounting member 44 intermediate the ends thereof. The pin 46 is rigidly attached at its upper end to the flexible member 44, and is inserted through the aperture 24 in the bimetallic member 14. An enlarged head portion 48 is located at the lower end of the pin 46 to prevent the free passage of such pin through the aperture 24. The aperture 24 is of such size and shape with respect to the pin 46 that there may be a relatively free movement therebetween. However, the head 48 of pin 46 will prevent the pin from passing through the bimetallic member 14. Therefore, it follows that the bimetallic member 14 may move upwardly with respect to the flexible mounting member 44 and movable contact 32 without causing any movement of the pin 46, flexible member 44 or contact 32 (see Fig. 2), and that, as the bimetallic member 14 bows downwardly, the engagement or cooperation of head 48 and bimetallic member 14 will cause the pin 46, resilient member 44 and movable contact 32 to be moved downwardly therewith.

It, therefore, follows that the central portion of the bimetallic member 14 may move toward the cooperating contacts 16 without causing any corresponding movement of the pin 46 and movable contact 32, but upon moving away from the cooperating contacts, such member will, through the cooperation of pin 46, cause the movable contact 32 to move therewith so as to disengage the cooperating contacts.

The adjusting device 18 comprises, in this instance, an adjusting screw 50 having a ball-head 52 at the lower end thereof and an adjusting knob 54 at the top end thereof, and a threaded sleeve 56 rigidly attached to the supporting structure 12. The sleeve 56 has an elongated threaded aperture (not shown) therethrough to permit the screw 50 to be operatively associated therewith. The screw 50 may thus be bodily moved vertically with respect to the supporting structure 12 by being rotated within the sleeve 56. The adjusting device 18 is positioned upon the supporting structure 12 in such a location that the lower ball-headed end 52 of the adjusting screw 50 will cooperate with the free end or movable end of the bimetallic member 14. The relative positions of the adjusting screw 50 thus determine the position of the free end of the bimetallic member 14 as the central portion thereof changes its direction from a rotative

flexing action to a bowing action, as hereinabove described. It is to be understood that the adjusting screw 50 may thus be selectively positioned to any desired location so as to selectively determine the operating characteristics of the bimetallic member 14.

When operating the thermostatic device 10 embodying my invention, the terminals 34 and 36 are operatively associated with a circuit which it is desired to have controlled by means of such device. Assuming that the bimetallic member 14 is in a relatively cold condition, the cooperative contacts 16 will be engaged (see Fig. 2). The bimetallic member 14 will thus be substantially horizontal parallel to the base 12. Then as the bimetallic member 14 increases in temperature, such member will rotatively flex upwardly about the spacer 26 as a fulcrum. The pin 46 and movable contact 32 will, however, remain substantially stationary while the bimetallic member 14 moves upwardly.

The free end of the bimetallic member 14 will continue its upward travel until it strikes the ball-headed end 52 of the adjusting screw 50. The bimetallic member 14 will thus, upon the continued increase in temperature, bow downwardly, whereupon the central portion thereof will reverse its direction of travel and start moving downwardly. With a continued downward travel of the central portion of the bimetallic member 14, such member will contact the head 48 of pin 46, causing said pin to be likewise moved downwardly. The flexible support member 44 and movable contact 32 of the cooperating contacts 16 will likewise be moved downwardly so as to disengage such cooperating contacts. The bimetallic member 14 thus rotatively flexes for a predetermined selected distance away from the high expansive side of the bimetallic member 40 and then bows in a reverse direction towards the high expansive side so as to actuate or disengage the cooperating contacts 16.

If it be desired to manually disengage the cooperating contacts 16, the adjusting screw 50 may be run down within the sleeve 56 so as to force the free end of the bimetallic member 14 downwardly or in a clockwise direction. This, in turn, through the cooperative action of pin 46 and flexible mounting member 44 causes the movable contact 32 to be separated from the stationary contact 30, disengaging the cooperating contacts 16 in a well-known manner. To reengage the cooperating contacts 16, it is thus necessary to manually rotate the adjusting screw 50 so that the free end of the bimetallic member 14 will be returned to its normal position, as hereinabove described.

Referring to Figs. 5 to 8, inclusive, I show a modified form of thermostat embodying my invention comprising a supporting structure 12', bimetallic member 14', cooperating contact 16' and adjusting device 18. The supporting structure 12' is similar to that illustrated in Figs. 1 to 4, inclusive, and as hereinabove described. Likewise, the bimetallic member 14' is substantially the same as hereinabove described, being rigidly attached to the supporting structure 12' by means of a spacer block 26 and screw 28. The adjusting device 18 is positioned upon the supporting structure 12' to selectively adjust the operating characteristics of the bimetallic member 14' in a manner as hereinabove described. The cooperating contact 16' comprises, in this instance, a movable contact 57 and a stationary contact 58. The movable contact 57 is rigidly

attached to and insulated from the bimetallic member 14' intermediate the ends thereof. The movable contact 56 includes a depending shaft or rivet portion 60 which is adapted to extend through the bimetallic member 14'. The lower end of the rivet portion 60 is riveted over upon a suitable washer 62 to rigidly attach the movable contact 57 to the central portion of the bimetallic member.

A suitable flexible member 64 is attached to the movable contact 57 and bimetallic member 14' at one end and to a terminal 66 at the other end. The flexible member 64 is located beneath the movable contact 57, and is, therefore, rigidly attached therewith to the bimetallic member 14', as hereinabove described. The flexible member 64, in this instance, extends through a suitable aperture 68 in the supporting structure 12', and is located alongside the terminal 66 to afford electrical connection therewith. The movable contact member 57 is thus rigidly attached to a point intermediate the ends of the bimetallic member 14 and resiliently attached to a terminal 66 of the thermostatic device 54.

The stationary contact 58 is rigidly attached to supporting structure 12', and is insulated therefrom by means of suitable insulating members 70. The contact 58 includes an upwardly extending rivet portion 72 which extends through the supporting structure 12' and a second terminal 74, whereupon the upper end thereof is riveted over against the terminal 74 to rigidly attach such contact and terminal to the supporting structure.

The bimetallic member 14' is physically similar to member 14 and is mounted upon the supporting structure in a manner similar to that hereinabove described. Such member will, therefore, when at a normal operating temperature, remain substantially horizontal. The cooperating contacts 16' are thus engaged (see Fig. 6), and the free end of the bimetallic member 14' is located somewhat below the ball-head 52 of the adjusting device 18.

With an increase in temperature of the bimetallic member 14', such member will tend to deflect upwardly. However, this action increases the contact pressure between the movable contact 57 and the stationary contact 58. With the increased temperature of the bimetallic member 14, the free end of such member will flex upwardly and engage the ball-head 52 of adjusting device 18, restraining any further upward movement of such member. The central portion of such member will then, upon a continued increase in temperature, change its direction of rotation and bow downwardly. The movable contact 57 rigidly attached thereto will correspondingly move downwardly. The cooperating contacts 16' will thus be disengaged. (see Fig. 7).

The adjusting device 18 may likewise manually disengage and reengage the cooperating contacts 16' as hereinabove described (see Fig. 8).

Still a further modification of the device embodying my invention is illustrated in Figs. 9 to 12, inclusive, in which I show a thermostatic device 80 comprising a supporting structure 82, a bimetallic member 84, cooperating contacts 86 and an adjusting device 88. The supporting structure 82 is substantially the same as the supporting structure 12, as hereinabove described. However, the structure 82 has a vertically extending cylindrical aperture 90 located at substantially the midpoint thereof to permit an insulating pin 92 to be slidably mounted therein

for a purpose hereinafter described. The bimetallic member 84 is substantially the same as the bimetallic member 14 hereinabove described. However, the high expansive portion of the bimetallic member 84 is located on the upper surface thereof. The free end of the bimetallic member 84 will thus move downwardly with an increasing temperature. The bimetallic member 84 is rigidly attached at one end to the supporting structure 82 by means of a spacer block 94 and screw 96 substantially as hereinabove described.

The cooperating contacts 86, in this instance, are located above the top surface of the supporting structure 82 and include a stationary contact 98 and a movable contact 100. The stationary contact 98 is rigidly attached to the terminal 102 by means of a rivet portion 104 thereof. The contact 98 and terminal 102 are insulated from the supporting structure 82 by means of suitable insulating washers 106. The movable contact 100 is rigidly attached to the free end of a flexible current carrying member 108. The rigid or stationary end of the flexible current carrying member 108 is located beneath a second terminal 110 which is rigidly attached to supporting structure 82 by means of a lower integral rivet portion 112. The flexible member 108 and terminal 110 are insulated from the supporting structure 82 by means of suitable insulating members 114. The flexible member 108 is located above the insulating pin 92, in such a manner that the pin 92 when biased upwardly will force the resilient member 108 and movable contact 100 upwardly, this action, in turn, causing the cooperating contacts 86 to be disengaged, as hereinafter described.

The pin 92 slidably mounted within the supporting structure 82 cooperates with the flexible member 108 at one end thereof and an intermediate point of the bimetallic member 84 at the other end thereof. Thus the bimetallic member 84 may, under suitable conditions, force the pin 92 upwardly so as to disengage or actuate the cooperating contacts 86.

The adjusting device 88 includes a threaded screw member 116 threadedly mounted within a sleeve 118. The screw 116 has a flange 120 located at the lower end thereof. The flange 120 is adapted to engage the free end of bimetallic member 84 as the adjusting screw 116 is run upwardly. The flange 120 is thus adapted to bodily move the free end of the bimetallic member 84 upwardly or selectively predetermine its operating limits.

When operating the thermostatic device 80 with the bimetallic member 84 at a normal temperature, such member will be substantially horizontal, (see Fig. 11). The cooperating contacts 86 will thus be engaged. Then as the bi-metallic member 84 increases in temperature, such member will rotatively flex downwardly about the spacer block 94 and screw 96 until the free end thereof engages the flange 120 of the adjusting device 88. The central portion of the bimetallic member 84 will then change its direction of movement and start to bow upwardly. This upward movement will thus cause the insulating pin 92 to likewise move upwardly. With a continued upward movement thereof, the pin 92 will first engage the flexible member 108 and then cause such flexible mounting member 108 and movable contact 100 to be moved upwardly, disengaging the cooperating contacts 86. The bimetallic member 84 will then, upon cooling suf-

ficiently, return to its original position with a reversal in the direction of movement of the central portion thereof and permitting the reengagement of the cooperating contacts 98 and 100

If it be desired to manually operate the thermostatic device 80, the adjusting screw 116 is moved upwardly in a vertical direction, whereupon the flange 120 thereof will force the free end of the bimetallic member 84 upwardly. The pin 92 will then be moved vertically so as to disengage the contact 100 in a manner hereinabove described. Then when it is desired to reengage the cooperating contacts 86, the adjusting screw is run down to its normal operating position in a well known manner.

It is, therefore, obvious that I have provided thermostatic devices which include a bimetallic member capable of rotatively flexing for a predetermined selective distance and then moving in an opposite direction to actuate the cooperating contacts.

Various other modifications may be made in the device embodying my invention without departing from the spirit and scope thereof, and I desire, therefore, that only such limitations shall be placed thereon as are imposed by the prior art and the appended claims.

I claim as my invention:

1. A thermostatic device comprising, in combination, cooperating contacts including a movable contact, a bimetallic member for actuating the movable contact, an adjusting device for selectively adjusting the operations of the member, and a flat spring attached to the movable contact and having a lost-motion connection with the bimetallic member for permitting free movement of the member below the selected contact-actuating value thereof and for bodily moving the movable contact above such actuating value.

2. A thermostatic device comprising, in combination, a terminal, cooperating contacts including a movable contact, a bimetallic member for actuating the movable contact, said movable contact being insulatedly attached to an intermediate point of the bimetallic member and resiliently attached to the terminal, an adjusting device for selectively adjusting the operation of the bimetallic member, said member adapted to increasingly bias the movable contact against the stationary contact until such member engages the adjusting device whereupon the member will change its curvature and separate the contacts.

3. A thermostatic device comprising, in combination, cooperating contacts including a movable contact, a resilient member carrying said movable contact, a bimetallic member for actu-

ating the movable contact and resilient member, an adjusting device adapted to cooperate with the moving end of such bimetallic member for selectively adjusting the operations of such member, said member adapted to rotatively flex towards the adjusting device and upon engaging the device to bow in an opposite direction between its rigid support and the device for actuating the movable contact and resilient member.

4. A thermostatic device comprising, in combination, a supporting structure, cooperating contacts including a movable contact, a bimetallic member for actuating the movable contact, and an insulating pin cooperating with the bimetallic member for transmitting the actuating movements of the member to the movable contact, said bimetallic member upon an increase in temperature adapted to flex away from the movable contact for a predetermined selective distance and then to bow towards the movable contact for actuation of such contact.

5. A thermostatic device including, in combination, cooperating contacts, a mechanical stop member, a thermal responsive device, and means other than said thermal responsive device for biasing said contacts to a certain position, said thermal responsive device under the influence of heat substantially continuously moving first in one direction until it engages said stop member and then in an opposite direction for thereafter effecting a single actuation of said means and a contact to a different position.

6. A thermostatic device including, in combination, normally closed contacts, a stop member, a bimetallic member, and separate resilient means for biasing said contacts to said closed position, said bimetallic member under the influence of heat changing its direction of curvature upon engaging said stop member while moving substantially continuously for thereafter effecting a single actuation of said means and a contact to a different position.

7. A thermostatic device including, in combination, cooperating contacts, an adjustable stop member, a bimetallic member, and a separate resilient member on which one of said contacts is mounted and which biases that contact to a given position, said bimetallic member upon being heated flexing with a given curvature a predetermined adjustable distance to engage said stop member and then bowing in a reverse direction to thereafter effect a single actuation of said resilient member and said one contact, said flexing and bowing constituting a substantially continuous movement.

EDWARD BLETZ.
